UNITED STATES PATENT OFFICE

FRANK E. DIAL AND ROY R. ROGERS, OF TERRE HAUTE, INDIANA

SAFETY DEVICE FOR PRESSES

Application filed September 14, 1928. Serial No. 306,038.

This invention relates to a guard for use in connection with an upright press, the primary object of the invention being to provide a guard which will be automatically moved to a position in front of the operator's hands on the down stroke of the press, to insure against injury to the hands of the operator should the operator attempt to remove the work from the machine before the completion of the down stroke.

Another object of the invention is to provide a device of this character which will be released when the press has completed its down stroke, so that the guard will be in a position to again be moved in front of the work, upon the next down stroke of the press. With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of an upright press equipped with a guard constructed in accordance with the invention.

Figure 2 is a front elevational view thereof.

Figure 3 is an enlarged detail view of the latching mechanism.

Figure 4 is a front elevational view of the latching mechanism.

Referring to the drawings in detail, the reference character 5 designates the frame of the press, which is of the usual and well known construction, the same being provided with bearings in which the shaft 6 operates, the shaft supporting the usual power wheel 7 at one end thereof.

The press includes a vertically movable member 8 operated by the movement of the shaft 6, there being provided the usual clutch mechanism 9 for throwing the machine into and out of operation. The clutch operating mechanism embodies the usual fork 10 that engages the clutch proper, the same being

mounted at one end of the bell crank 11, the opposite end thereof being connected with the link 12 which also has connection with the vertically movable control rod 13, there being provided a coiled spring 14 surrounding the link 12 to normally hold the clutch member in its inactive position.

The rod 13 extends downwardly and connects with the foot lever 15 which is pressed by the foot of the operator to throw the clutch into operation to operate the press. The guard is mounted on the outer end of the pivoted arm 16, and is indicated by the reference character 17, the arm being pivotally connected to the frame of the press at 18. Connected with the arm 16 is an operating rod 19 that also connects with the foot lever at 20 so that as the foot lever is pressed downwardly to operate the press, the guard is swung from a position as shown in full lines in Figure 1, to a position as indicated in dotted lines.

The foot lever 15 is returned to its normal position by means of the rod 21 that connects therewith, there being provided a coiled spring 22 surrounding the rod to lift the rod and foot lever connected therewith. A coiled spring 23 has connection with the arm 16 to return the arm to its inactive position.

Positioned at the front of the machine is a pivoted latch member 24 that has an arm 25 which extends laterally therefrom, when the guard is in its inactive position, as shown by Figure 2 of the drawings. This arm lies in the path of travel of the arm 16 when the arm 16 moves downwardly, to the end that the latch member 24 is moved to a position as shown by Figure 4 of the drawings. Arm 26 now extends laterally and lies in the path of travel of upward movement of the arm 16. A pivoted latch 27 is adapted to engage the latch 24 when it has been moved to its locking position, to temporarily hold the latch 24 against movement. Thus it will be obvious that as the arm 16 moves downwardly it will contact with the arm 25 moving the latch member 24 to a position as shown by Figure 4, the latch member 27 acting to hold the latch member 24 in its locked position.

with the result that the arm 26 will hold the arm 16 against return movement.

The vertically movable member 8 of the press carries an arm 28 that extends downwardly and laterally and is designed to ride over the curved surface 29 of the latch member 27 to move the latch member 27 to its inactive position releasing the latch member 24.

This action takes place when the vertically movable member 8 reaches the limit of its downward movement, so that the guard and latch members will assume their inactive positions to be operated on the next down stroke of the vertically movable member. Supported on the frame of the machine is a pivoted locking arm 30 which is connected with the rod 13 so that as the rod moves downwardly, the lower end 31 of the locking arm 30 will move to a position directly over the latch member 24 and hold the latch member 20 against movement as long as the rod 13 is held down, but when the rod 13 is released, it is obvious that the member 24 will return to its inactive position, releasing the latch member 24.

Since the operation of the arm 30 depends on the movement of the clutch actuating rod 13, it will be seen that should the clutch mechanism become inoperative and the rod 30 fail to move upwardly, the locking arm 30 will remain in its active position to hold the guard in its active position. It might be further stated that the latch member 27 is moved against the tension of the coiled spring 32 so that the latch member is normally held in its active position.

When the arm 16 moves downwardly, it engages the arm 25 and moves the latch member to a position as shown by Figure 4, in which position the latch member 27 moves under the lower edge of the latch member 25, see Figure 4, to hold the arm 16 in its lowest position. The arm 16 is held in this position until the rod 28 moves over the latch member 27 to cause the latch member 27 to disengage the member 24, whereupon arm 16 engages the arm 26, moving the arm 26 upwardly, and returning the latch member 24 to its normal position as shown by Figure 2. This action of course takes place upon the upward or return movement of the arm 16, caused by the action of the spring 23.

We claim:

In a press guard, a frame, a power clutch, a vertically movable pressing member, an arm pivotally mounted on the frame, a guard arm pivotally mounted on one end of the arm and extended laterally to a position at the front of the pressing member, a foot lever, a rod connecting the foot lever and power clutch, a rod connecting the foot lever and arm to move the arm and guard to their active positions when the foot lever is operated to operate the clutch, a pivoted latch operated by the downward movement of the arm, and adapted to hold

the arm in its active position, a latch for holding the first mentioned latch in its active position, means controlled by the downward movement of the pressing member for releasing the last mentioned latch to release the first mentioned latch, and yieldable means for returning the arm and guard to their normal positions.

In testimony that we claim the foregoing as our own, we have hereto affixed our signatures.

FRANK E. DIAL.
ROY R. ROGERS.
